CLAIM

The ornamental design for a display panel or portion thereof with a graphical user interface, as shown and described.

DESCRIPTION

The FIGURE is a front view of a display panel or portion thereof with a graphical user interface.

The broken lines showing the display panel or portion thereof forms no part of the claimed design. The other broken lines in the FIGURE and the areas within the broken lines show portions of the graphical user interface that form no part of the claimed design.

1 Claim, 1 Drawing Sheet
